UNITED STATES PATENT OFFICE.

JULES H. VENON, OF NEW YORK, N. Y.

DESIGN FOR A PLATE OR SIMILAR ARTICLE.

40,711.

Specification for Design.

Patented May 31, 1910.

Application filed February 25, 1910. Serial No. 546,034. Term of patent 7 years.

To all whom it may concern:

Be it known that I, JULES H. VENON, a citizen of the United States, and resident of the city, county, and State of New York, have invented a new, original, and ornamental Design for Plates or Similar Articles, of which the following is a specification, reference being had to the accompanying drawing, forming part thereof.

The figure is an elevation of a china plate, showing my new design.

The design comprises a china plate or

similar article, having a decoration composed of flowers and leaves, which may be variously tinted or colored, placed around the edge thereof, substantially as shown in the drawing.

I claim:

The ornamental design for a plate or similar article, as shown and described.

JULES H. VENON.
